DESIGN FOR A HANDBAG

William L. M. Clark, St. Louis, Mo., assignor to
W. L. M. Clark, Inc., St. Louis, Mo., a corporation of Missouri

Application October 10, 1938, Serial No. 80,349

Term of patent 3½ years

To whom it may concern:

Be it known that I, William L. M. Clark, a citizen of the United States, residing in the city of St. Louis and State of Missouri, have invented a new, original, and ornamental Design for Handbags, of which the following is a specification, reference being had to the accompanying drawing, forming part thereof, in which

I claim:

The ornamental design for a handbag as shown and described.

WILLIAM L. M. CLARK.
